(57) **CLAIM**

I claim the ornamental design for a promotional vehicle, as shown and described.

DESCRIPTION

FIG. 1 is a perspective view of the promotional vehicle of the present invention having panels in a closed position;

FIG. 2 is a front view of the promotional vehicle, having panels in a closed position;

FIG. 3 is a rear view of the promotional vehicle, having panels in a closed position;

FIG. 4 is a left side view of the promotional vehicle having panels in an open position;

FIG. 5 is a right side view of the promotional vehicle having panels in an open position;

FIG. 6 is a top view of the promotional vehicle having panels in a closed position; and,

FIG. 7 is a perspective view of the promotional vehicle, having panels in an open position.

The broken lines shown throughout the drawing views are for illustrative purposes only and form no part of the claimed design.
